VARIABLE DISPLACEMENT HYDRAULIC APPARATUS

William W. Headings, Willoughby, and Howard E. Rose, Hudson, Ohio, assignors to Borg-Warner Corporation, Chicago, Ill., a corporation of Illinois

Filed Mar. 30, 1959, Ser. No. 802,821

2 Claims. (Cl. 103—162)

This invention relates to a variable displacement hydraulic apparatus, and, in particular, relates to a piston type pump or motor having means to vary the amount of fluid displaced by the pump.

The conventional piston type pump or motor comprises a housing having a cavity formed therein. A block is rotatably supported in the cavity and is provided with a plurality of cylinders passing therethrough and being disposed in circular array around the axis of rotation of the block. A rotatable member, having an axis of rotation disposed angularly with respect to the axis of rotation of the block, is rotatably supported within the cavity of the housing and is operatively interconnected with the cylinder block. The rotatable member carries a plurality of pistons having portions thereof disposed respectively in the cylinders formed in the block. Since the axis of rotation of the rotatable member is disposed angularly with respect to the axis of rotation of the block, rotation of the rotatable member effects rotation of the cylinder block and reciprocative movement of each piston within its respective cylinder when the hydraulic apparatus is acting as a fluid pump. Conversely, when the hydraulic apparatus is operating as a hydraulic motor, the pistons are reciprocated within their respective cylinders by fluid pressure and thereby cause rotation of the rotatable member, the rotatable member, in turn, effecting rotation of the cylinder block interconnected therewith.

When the pistons are reciprocated through the angular relation of the rotatable member and block, each piston reaches its bottom dead center position when the respective piston has moved its maximum distance in one direction within the respective cylinder and further movement thereof will be in the opposite direction. Similarly, each piston reaches its top dead center position when the respective piston has moved its maximum distance in the other direction within the respective cylinder and further movement thereof will be in the opposite direction.

When the hydraulic apparatus is operating as a hydraulic pump, each piston, when being reciprocated within its respective cylinder from its bottom dead center position to its top dead center position by the rotational movement of the rotatable member, is adapted to draw fluid through an inlet formed in the housing into the respective cylinder. As each piston is reciprocated from its top dead center position back to its bottom dead center position, the respective piston acts against the fluid previously drawn within the respective cylinder and forces the same out through an outlet formed in the housing. Similarly, when the hydraulic apparatus is operating as a hydraulic motor, pressure fluid delivered through the inlet to each cylinder acts against the end of the respective piston and causes the same to move from its bottom dead center position to its top dead center position thereby effecting rotational movement of the rotatable member. Since the rotatable member is interconnected with the rotatable block, the rotatable member causes rotation of the block and causes each piston to move from its top dead center position back to its bottom dead center position to thereby expel the fluid previously received within the respective cylinder out through the outlet.

Movement of each piston from its bottom dead cen-

2

ter position to its top dead center position is generally referred to as the intake stroke of the piston regardless of whether the hydraulic apparatus is being utilized as a hydraulic pump or motor. Similarly, the movement of each piston from its top dead center position to its bottom dead center position is referred to as the discharge stroke of the piston regardless of whether the hydraulic apparatus is being utilized as a hydraulic pump or motor.

In order to interconnect the inlet with the cylinders wherein the respective pistons are moving or are to be moved from their bottom dead center positions to their top dead center positions, and to simultaneously interconnect the outlet with the cylinders wherein the respective pistons are moving from their top dead center positions to their bottom dead center positions, a suitable non-rotatable valve plate is disposed in the housing cavity between the cylinder block and the inlet and outlet. The valve plate is formed with a pair of arcuately shaped openings. One of the openings formed in the valve plate is fluidly interconnected with the inlet and is so constructed and arranged to place the inlet in fluid communication with each cylinder during substantially the complete intake stroke of the respective piston. The other opening is fluidly interconnected with the outlet and is adapted to interconnect the outlet with each cylinder during substantially the complete discharge stroke of the respective piston.

In order to vary the displacement of a hydraulic apparatus of the previously described type without changing the speed of the operation thereof when acting as a pump or without changing the pressure value of the pressure fluid when acting as a motor, i.e., to vary the actual amount of fluid which is permitted to pass from the inlet to the outlet when the hydraulic apparatus is operating at a constant speed as a hydraulic pump or when operating with a constant pressure value of the pressure fluid when acting as a hydraulic motor, some means must be provided to vary the effective strokes of the pistons by varying the actual movement thereof or varying the actual amount of fluid displaced by the pistons from the inlet to the outlet without changing the actual movement of the pistons.

One means for varying the displacement of a hydraulic apparatus of the previously described type has been to vary the angular position of the axis of rotation of the rotatable member relative to the axis of rotation of the cylinder block by moving the rotatable member relative to the cylinder block or the cylinder block relative to the rotatable member. However, in this prior known device, although the actual movement of each piston between its bottom dead center position and its top dead center position has been reduced in order to provide for variable displacement, complex structure must be provided in order to vary the angular position of the cylinder block relative to the rotatable member thereby increasing production and maintenance costs.

Another means for varying the displacement of a hydraulic apparatus of the previously described type has been designed which varies the time that the valve plate permits fluid communication between the inlet and the cylinders wherein the respective pistons are moving from their bottom dead center positions toward their top dead center positions. However, in this prior art design, when it is desired to have a partial displacement or zero displacement condition, each cylinder, during at least a portion of the intake stroke of the respective piston, is not interconnected with the inlet whereby movement of the respective piston creates a vacuum condition in its respective cylinder until the valve plate permits the inlet to be fluidly interconnected therewith. Because a vacuum condition is

created within each cylinder before it is interconnected with the inlet, the resulting rush of fluid from the inlet into the cylinder when the cylinder is eventually interconnected therewith tends to break down the surfaces of the valve plate and/or the cylinders, this rupture of the surfaces occurring by the well-known adverse cavitation condition created and causing malfunctioning of the hydraulic apparatus.

Therefore, it has been found that a hydraulic apparatus of the previously described type can be produced with means for varying the displacement thereof without changing the angular position of the rotatable member relative to the cylinder block and without having the cavitation disadvantage, and it is an object of this invention to provide such a hydraulic apparatus.

It is, therefore, an object of this invention to provide an improved variable displacement hydraulic apparatus.

Another object of this invention is to provide a piston type hydraulic apparatus having means for varying the displacement thereof.

A further object of this invention is to provide a hydraulic apparatus of the piston type having means for interconnecting the inlet and outlet with a cylinder at different positions of the respective piston in order to vary the displacement of the hydraulic apparatus.

A more specific object of this invention is to provide a hydraulic apparatus comprising a housing having a chamber and an inlet and an outlet leading respectively to and from the chamber, fluid displacing means disposed in the chamber adapted to receive fluid from the inlet and deliver the same out through the outlet upon movement of the fluid displacing means, a movable valve element disposed in the chamber between the fluid displacing means and the inlet and outlet and being adapted to interconnect the inlet and outlet with the fluid displacing means, and means for moving the valve element relative to the fluid displacing means to interconnect the inlet and outlet with the fluid displacing means at different positions of the fluid displacing means to vary the displacement of the apparatus.

Other and more particular objects, advantages and uses of this invention will become apparent from a reading of the following specification taken in connection with the accompanying drawings forming a part thereof and wherein:

FIGURE 1 illustrates, in an axial cross-sectional view, a hydraulic apparatus formed in accordance with the teachings of this invention.

FIGURE 2 illustrates, in a cross-sectional view, certain operating parts of the hydraulic apparatus illustrated in FIGURE 1 and is taken on line 2-2 thereof.

FIGURE 3 illustrates, in a partial cross-sectional view, certain other operating parts of the hydraulic apparatus illustrated in FIGURE 1 and is taken on line 3-3 thereof.

FIGURE 4 is a cross-sectional view of the hydraulic apparatus illustrated in FIGURE 1 and is taken on line 4-4 thereof.

FIGURE 5 illustrates, in a schematic view, a portion of the hydraulic apparatus illustrated in FIGURE 1.

FIGURE 6 illustrates, in a schematic view similar to FIGURE 2, certain operating parts of the hydraulic apparatus illustrated in FIGURE 1.

FIGURE 7 is a partial cross-sectional view similar to FIGURE 2 and illustrates particular operating positions of certain parts of the hydraulic apparatus illustrated in FIGURE 1.

FIGURE 8 illustrates, in a view similar to FIGURE 7, other operating positions of the parts illustrated in FIGURE 7.

FIGURE 9 illustrates, in a partial cross-sectional view, other operating positions of the parts illustrated in FIGURE 4.

Reference is now made to the accompanying drawings wherein like reference letters and numerals are used throughout the various figures to designate like parts where appropriate, and particular reference is made to

FIGURE 1 illustrating a hydraulic apparatus, generally indicated by the reference letter A, formed in accordance with the teachings of this invention and including a housing 10 comprising a plurality of housing sections 11 and 12 suitably secured together in aligned relation in a manner well known in the art.

The housing section 11 has a flat end wall 13 interrupted by a stepped bore means 14 comprising a plurality of cylindrical bore sections 15, 16 and 17, the bore sections 15, 16 and 17 respectively having diameters substantially smaller than the preceding section and being disposed coaxially along an axis 18 of the stepped bore means 14. Another end wall 19 of the housing section 11 is interrupted by a stepped bore means 20 comprising a plurality of bore sections 21, 22 and 23, the bore sections 21, 22 and 23 respectively having diameters substantially smaller than the preceding sections and being disposed coaxially along an axis 24 of the stepped bore means 20. The axis 18 of the stepped bore means 14 angularly intersects the axis 24 of the stepped bore means 20, the stepped bore means 14 and 20 cooperating to define a chamber B within the housing 10. The chamber B is fluidly interconnected with the exterior of the housing 10 by a suitable drain port 25 formed in the housing section 11.

The housing section 12 is provided with a substantially flat end wall 26 which is adapted to sealably abut the flat end wall 13 of the housing section 11 when the housing sections 11 and 12 are secured together. The end wall 26 is adapted to close off one end of the chamber B.

A cylindrical cylinder block 27 is disposed within the stepped bore means 14 of the cavity B and is supported for rotation about the axis 18 by bearing means 28, the bearing means 28 being disposed between a sleeve 29 telescopically disposed within the bore section 16 and the cylinder block 27. The sleeve 29 is provided with an annular groove 30 at one end thereof adapted to cooperate with the bore section 15 to provide an annular groove 31. A suitable sealing means 32 is disposed in the annular groove 31 and is utilized to seal the housing sections 11 and 12 together.

The cylinder block 27 is provided with a tubular projection 33 extending from a flat side 34 thereof, the flat side 34 being disposed substantially parallel to and spaced from another flat side 35 of the cylinder block 27. A plurality of cylinders 36 are formed in the cylinder block 27 and interconnect the flat sides 34 and 35. One end 37 of each cylinder 36 is reduced and is adapted to cooperate with a rotatable valve plate 38 in a manner later to be described.

The valve plate 38 is disposed in the cavity B between the cylinder block 27 and the flat end wall 26 of the housing section 12, the valve plate 38 having a pair of spaced opposed flat surfaces 39 and 40 disposed respectively in sealing engagement with the flat end wall 26 of the housing section 12 and the flat side 35 of the cylinder block 27.

A plurality of pistons 41 each having an enlarged head portion 42 are disposed respectively in the cylinders 36. Each piston 41 has a substantially spherical end portion 43 secured within a respective socket 44 formed in one end of a rotatable member 45. The rotatable member 45 is disposed within the bore means 20 of the housing section 11 and is supported for rotation about the axis 24 by a plurality of bearing means 46 interposed between the rotatable member 45 and a sleeve 47 having a portion thereof telescopically received within the bore section 22. The sleeve 47 is suitably secured to the housing section 11 by a plurality of bolts 48 passing through a plurality of apertures 49 formed in a flanged portion 50 of the sleeve member 47, the flanged portion 50 being telescopically received within the bore section 21 of the housing section 11.

The rotatable member 45 has an end 51 thereof interrupted by a bore 52 which terminates within the rotatable

member 45. The bore 52 of the rotatable member 45 is internally splined at 53 in order to be interconnected to an externally splined end 54 of a shaft 55 projecting from the end 19 of the housing 10. The shaft 55 provides a drive member when the apparatus A is utilized as a hydraulic pump and provides a power take off member when the apparatus A is utilized as a hydraulic motor.

The rotatable member 45 is provided with a substantially spherical end portion 56 adapted to be telescopically received within the tubular portion 33 of the cylinder block 27. The spherical end portion 56 of the rotatable member 45 carries a plurality of pins 57 projecting radially therefrom and being respectively received within a plurality of slots 58 formed in the tubular portion 33 of the cylinder block 27, the pins 57 and slots 58 operatively interconnecting the rotatable member 45 and cylinder block 27 together. In this manner, rotational movement of the rotatable member 45 causes rotational movement of the cylinder block 27 through the driving relation of the pins 57 and the slots 58 formed in the tubular portion 33 of the cylinder block 27. Since the axis 24 of rotation of the rotatable member 45 is angularly disposed with respect to the axis 18 of rotation of the block 27, the spherical end 56 of the rotatable member 45 and the slots 58 of the block 27 permit relative movement between the block 27 and the rotatable member 45 to compensate for this angular relation.

When the rotatable member 45 is rotated, each piston 41 carried by the rotatable member 45 is reciprocated relative to the block 27 within the respective cylinder 36, the pistons 41 each moving from a bottom dead center position 59 as shown in FIGURE 3 to a top dead center position 60 upon 180 degrees of rotational movement of the rotatable member 45 and moving from a top dead center position 60 to a bottom dead center position 59 upon a further rotational movement of 180 degrees of the rotatable member 45 because of the angular relation of the respective axes 18 and 24 of rotation of the block 27 and member 45.

The valve plate 38 is provided with a pair of kidney shaped openings 61 and 62 respectively interconnecting the opposed sides 39 and 40 thereof (see FIGURES 1, 4 and 9). The opening 61 in the valve plate 38 is fluidly interconnected with an inlet 63 formed in the housing 10. The other opening 62 formed in the valve plate 38 is in fluid communication with an outlet 64 formed in the housing 10. The inlet 63 interrupts the flat end wall 26 of the housing section 12 and defines a kidney shaped opening 63a adapted to cooperate with the valve plate inlet opening 61. Similarly, the outlet 64 interrupts the flat end wall 26 of the housing section 12 and defines a kidney shaped opening 64a adapted to cooperate with the valve plate outlet opening 62.

The valve plate 38 is provided with a centrally disposed internally splined bore 65 adapted to receive a splined end 66 of a rotatable shaft 67 of a motor C later to be described. The valve plate 38, therefore, is mounted for rotational movement about an axis of rotation 68 which is disposed coincident with the axis 18 of rotation of the cylinder block 27.

As shown in FIGURE 4, the inlet opening 61 and the outlet opening 62 formed in the valve plate 38 are equally spaced on opposite sides of a plane 69 passing respectively through the points 59 and 60 where each piston 41 reaches its respective bottom dead center position 59 and its top dead center position 60. The valve plate 38 is adapted to be rotated about the axis 68 in a counterclockwise direction from the position illustrated in FIGURE 4 to the position illustrated in FIGURE 9 upon rotation of the shaft 67 in a manner later to be described. As illustrated in FIGURE 9, the inlet opening 61 and the outlet opening 62 are each bisected by the plane 69, i.e., one half of each opening 61 and 62 is disposed respectively on opposite sides of the plane 69. As the valve plate 38 is rotated 90 degrees from the position illustrated

in FIGURE 4 to the position illustrated in FIGURE 9, the inlet opening 61 remains in fluid communication with the inlet 63 through the cooperation of the kidney shaped opening 63a and the inlet opening 61. Similarly, the outlet opening 62 remains in fluid communication with the outlet 64 through the cooperation of the kidney shaped opening 64a and the outlet opening 62.

The operation of the hydraulic apparatus A, as set forth above, will now be described. Assuming that the hydraulic apparatus A is operating as a hydraulic pump and the valve plate 38 is in the position illustrated in FIGURE 4, a suitable power source (not shown) is interconnected with the shaft 55 and causes rotation thereof in a clockwise direction as viewed in FIGURE 3. Since each piston 41 is carried by the rotatable member 45, and, therefore, is rotated therewith, each piston is reciprocated within the respective cylinder 36 as the piston 41 is rotated from its bottom dead center position 59, to its top dead center position 60, and back to its bottom dead center position 59.

When each piston is at its bottom dead center position 59, the opening 37 of the respective cylinder 36 comes into fluid communication with the inlet opening 61 in the valve plate 38. As each piston 41 is rotated from its bottom dead center position 59 to its top dead center position 60, the respective piston 41 draws fluid from the inlet 63 into the respective cylinder 36 as the cylinder 36 remains in fluid communication with the inlet opening 61 throughout substantially the entire intake stroke of the piston 41. As each piston 41 is rotated to its top dead center position 60, the respective cylinder 36 moves out of fluid communication with the inlet opening 59 whereby the fluid drawn into the cylinder 36 is completely trapped therein. Upon further movement of each piston 41 in a clockwise direction, as viewed in FIGURE 3, the respective piston 41 begins to move toward its bottom dead center 59. As each piston 41 is rotated past its top dead center position 60, the respective cylinder 36 comes into fluid communication with the outlet opening 62 formed in the valve plate 38 whereby movement of the piston from its top dead center position 60 to its bottom dead center position 59 expels the fluid previously received within the respective cylinder 36 out through the outlet 64. As long as the valve plate 38 remains in the position illustrated in FIGURE 4, the inlet 63 remains in fluid communication with each cylinder 36 during substantially the entire intake stroke of the respective piston 41 and the outlet 64 remains in fluid communication with the respective cylinder 36 during substantially the entire discharge stroke of the respective piston 41 whereby the apparatus A is operating at its maximum displacement condition for a particular speed of rotation of the drive shaft 55 as the entire amount of fluid drawn into each cylinder 36 from the inlet 63 is delivered to the outlet 64.

When the valve plate 38 has been rotated to the position illustrated in FIGURE 9, by any suitable means, the hydraulic apparatus A will be operating at its zero displacement condition in the following manner. As previously described, when each piston 41 is rotated and is moved past its bottom dead center position 59, the respective piston 41 begins its intake stroke, drawing fluid into the respective cylinder 36. However, as shown in FIGURE 9, when each cylinder 36 is rotated counterclockwise past point 59, the respective piston draws fluid therein from the outlet 64 as the outlet opening 62 is in fluid communication with the respective cylinder 36 during the first half of the intake stroke of the respective piston 41. During the last half of the intake stroke of each piston 41, the respective cylinder 36 comes into communication with the inlet opening 61 whereby the respective piston 41 draws half of the fluid filling the respective cylinder 36 from the outlet 64 and the remaining half from the inlet 63. As each piston moves past its top dead center position 60, the respective cylinder 36 is disposed in fluid

communication with the inlet opening 61 of the valve plate during half of the discharge stroke of the respective piston 41 whereby the respective piston 41 expels half of the fluid previously drawn into the cylinder 36 back to the inlet 63. During the last half of the discharge stroke of the respective piston 41, the respective cylinder 36 comes into fluid communication with the outlet opening 62 of the valve plate 38 whereby the remaining fluid in the cylinder 36 is expelled to the outlet 64. Therefore, since half of the fluid received within each cylinder 36 is drawn from the outlet 64 and the other half is drawn from the inlet 63, and since half the fluid received in each cylinder 36 is discharged to the inlet 63 and the other half to the outlet 64, the net displacement of the hydraulic apparatus is zero, i.e., the actual amount of fluid delivered from the inlet 63 to the outlet 64 is zero.

As the valve plate 38 is rotated from the position illustrated in FIGURE 4 providing maximum delivery toward the position illustrated in FIGURE 9 providing zero delivery, the delivery of the hydraulic apparatus A is progressively and infinitely reduced as each cylinder 36 is placed in fluid communication with the outlet opening 62 during a greater portion of the intake stroke and with the inlet opening 61 during a greater portion of the discharge stroke until zero delivery is reached. Conversely, when the valve plate 38 is moved from the position illustrated in FIGURE 9 toward the position illustrated in FIGURE 4, the delivery of the hydraulic apparatus A will be progressively and infinitely increased as each cylinder 36 is placed in fluid communication with the inlet opening 61 during a greater portion of the intake stroke and with the outlet opening 62 during a greater portion of the discharge stroke until maximum delivery is reached. Therefore, when the valve plate 38 is disposed in any position between its maximum and zero delivery positions the hydraulic apparatus A will be operating at a partial delivery condition. By changing the delivery from the hydraulic apparatus A, as described above, the overall displacement by the apparatus A is varied.

Although the operation of the hydraulic apparatus A has been described when operating as a hydraulic pump, it is to be understood that the operation thereof occurs in substantially the same manner when operating as a hydraulic motor, the valve plate 38 regulating the amount of pressure fluid delivered to each cylinder 36 and thus the power output of the apparatus A. The valve plate 38, therefore, regulates the intake of the hydraulic apparatus A when operating as a hydraulic motor, i.e., varies the actual amount of fluid that passes from the inlet 63 to the outlet 64.

It is to be understood that many means could be provided for selectively varying the position of the valve plate 38 to provide for variable delivery by the hydraulic apparatus A. One such means will now be described.

As previously stated, the valve plate 38 is rotatably mounted on a rotatable shaft 67 of a motor C, the motor C being disposed within a bore 70 formed in the housing 10. The shaft 67 has an enlarged cylindrical portion 71 telescopically received within a stationary tubular member 72 disposed within the bore 70. The tubular member 72 has a flanged portion 73 at one end thereof, the flanged portion 73 having a substantially flat surface 74 sealably abutting a shoulder 75 formed at the juncture of the bore 70 with a smaller counter bore 76 formed in the housing 10. The counter bore 76 is coaxially disposed with respect to the bore 70 and terminates within the housing section 12 defining an end wall 77 therein. A washer-like member 78 is disposed in the counter bore 76 and surrounds the cylindrical portion 71 of the shaft 67. The washer-like member 78 is provided with a pair of opposed flat sides 79 and 80, the side 80 being disposed in sealing relation with the end wall 77 and the side 79 being disposed spaced from the flat surface 74 of the tubular member 72. The flat surfaces 74 and 79 of the respective members 72 and 78 cooperate to-

gether with the shaft portion 71 and the housing 10 to define a sealed annular cavity 81.

A slot 82 is formed radially through the cylindrical portion 71 of the shaft 67 and is adapted to receive a vane 83, the vane 83 projecting radially on each side of the cylindrical portion 71 to define a pair of fins or vanes 84 and 85 disposed in the annular cavity 81. An annular member 86 is disposed within the annular cavity 81 and has an external peripheral surface 87 disposed in sealing engagement with the internal peripheral surface of the housing 10, the internal peripheral surface of the housing 10 being defined by the counter bore 76. An internal peripheral surface 88 of the annular member 86 is adapted to be sealably engaged by the fins or vanes 84 and 85 carried by the shaft 67.

The annular member 86 is provided with an annular groove 89 interrupting the external peripheral surface 87 thereof, the annular groove 89 being disposed in fluid communication with a passage 90 formed in the housing 10 and leading to a control valve D later to be described. The annular member 86 carries a pair of stop means 91 and 92 projecting from flange 73. The stop means 91 and 92 have arcuately shaped ends 93 adapted to be disposed in sealing engagement with the cylindrical portion 71 of the shaft 67. The stop members 91 and 92 respectively cooperate with the fins or vanes 84 and 85 to define a pair of chambers 94 and a pair of chambers 95, the chambers 95 being respectively disposed in fluid communication with the bore 70 by passages 96 formed in the flanged portion 73 of the tubular member 72.

A coiled torsional spring 97 is disposed within the bore 70 and has a radially inwardly projecting end 98 received in a slot 99 formed in the tubular member 72 and another radially inwardly projecting end 100 thereof projecting through a slot 101 formed in the sleeve member 72 and received within a slot 102 formed in the cylindrical member 71 of the shaft 67. Since the tubular member 72 is fixed relative to the housing 10 by a pin 103 projecting through the housing section 12 and being received in a slot 104 formed in the flanged portion 73 thereof, the torsional spring 97 tends to rotate the shaft 67 in a clockwise direction when looking at FIGURE 2 whereby the fins 84 and 85 are respectively disposed in engagement with the stop means 91 and 92 and the valve plate 38 is disposed in the maximum displacement position illustrated in FIGURE 4.

The chambers 94 are respectively placed in fluid communication with the annular groove 89 formed in the annular member 86 by ports 105 formed in the annular member 86, the ports 105 thereby fluidly interconnecting the chambers 94 with the passage 90 formed in the housing 10 and leading to the control valve D.

The control valve D includes a stepped bore means 106 formed in the housing 10, the bore means 106 having a plurality of cylindrical bore sections 107, 108, and 109. A sleeve member 110 is disposed within the bore section 109 and has a flanged end portion 111 disposed within the bore section 108. The sleeve 110 is maintained within the bore means 106 by a tubular plug member 112 threadedly received within the bore section 107 and disposed in engagement with the flanged portion 111 of the sleeve 110. The sleeve 110 is provided with a central bore 113 passing therethrough and is adapted to telescopically receive a cylindrical valve member 114 therein. The sleeve 110 is provided with a pair of spaced annular grooves 115 and 116, the annular groove 115 being disposed in fluid communication with the passage 90 leading to the motor C and the annular groove 116 being disposed in fluid communication with a passage 117 formed in the housing section 12 and leading to the bore 70. The annular groove 115 is, in turn, placed in fluid communication with the bore 113 formed in the sleeve 110 by a plurality of ports 118. Similarly, the annular groove 116 is placed in fluid communication with the bore 113 by a plurality of ports 119.

The valve member 114, telescopically received within the bore 113 or the sleeve 110, is disposed in sealing engagement therewith but is adapted to be axially movable relative thereto. The movable valve member 114 is provided with a pair of spaced annular grooves 120 and 121 which define a sealing land portion 122 therebetween. The land 122 is of sufficient length to completely seal off the ports 118 from the annular grooves 120 and 121 when the valve member 114 is disposed in the position illustrated in FIGURE 2. The valve member 114 is provided with a pair of ends 123 and 124, the end 124 being interrupted by a bore 125 which terminates within the member 114 and communicates with a port disposed within land 122 in order to convey intermediate fluid pressure to the inside of plug member 112. A pin 126 is disposed within the bore 125 of the member 114 and is carried by a cradle member 127 disposed within the tubular member 112. A compression spring 128 is interposed between the plug member 112 and the cradle member 127 and tends to urge the member 114 to the right as viewed in FIGURE 2.

The outlet 64 is interconnected with the end of the bore section 109 by a passage 129 formed in the housing 10. In this manner, pressure fluid within the outlet 64 is adapted to act on the end 123 of the member 114 and tends to move the member 114 to the left, as viewed in FIGURE 2, in opposition to the combined force of the compression spring 128 and the force of the intermediate fluid pressure acting on the end 124 of valve member 114. The force of the compression spring 128 can be selectively predetermined by adjusting the position of the plug member 112 relative to the housing 10 in a manner well known in the art.

The bore 70 of the motor C is fluidly interconnected with the inlet 63 by a passage 130.

The control valve D and motor C cooperate with the valve plate 38 of the hydraulic apparatus A to vary the displacement of the apparatus A when operating as a hydraulic pump in accordance with the pressure value of the pressure fluid delivered to the outlet 64 and acting against the end 123 of the control valve member 114. In this manner, the hydraulic apparatus A will be prevented from delivering pressure fluid to the outlet 64 above a predetermined pressure value, the predetermined pressure value being determined by the particular compression setting of the spring 128 of the control valve D.

The operation of the hydraulic apparatus A utilizing the control valve D and motor C will now be described.

Assuming that the hydraulic apparatus A is operating as a hydraulic pump and that it is desired that the pressure value of the pressure fluid delivered to the outlet 64 thereby will not exceed a predetermined pressure value, such as 3,000 p.s.i., the compression force of the spring 128 is set accordingly. Upon initial rotation of the drive shaft 55 by a suitable power source (not shown) driving the shaft at a constant speed, the valve plate 38 will be maintained in the position illustrated in FIGURE 4 providing for maximum displacement of the hydraulic apparatus A by the torsional spring 97 in the manner previously described. As the hydraulic pump A receives fluid from the inlet 63 and delivers the same out through the outlet 64, the outlet 64 being restricted in a manner well known in the art so that the fluid delivered thereto is placed under pressure, the pressure value of the pressure fluid in the outlet 64 increases. As long as the pressure value of the pressure fluid in the outlet 64 remains below 3,000 p.s.i., the control valve member 114 is moved by the force of the spring 128 to right from the position illustrated in FIGURE 2 preventing any fluid communication between the outlet 64 and the motor C and placing the passages 90 and 117 in fluid communication by the annular groove 121 overlapping the ports 118 and 119.

When the pressure value of the pressure fluid delivered to the outlet 64 reaches 3,000 p.s.i., the valve member 114 is moved to the left to the position illustrated in FIGURE

2 whereby fluid communication between the outlet 64 and motor C is still prevented by the land 122 of the valve member 114. However, when the valve member is placed in the position illustrated in FIGURE 2, fluid communication is now prevented between the passages 90 and 117 and thus between the chambers 95 and the inlet 63.

If the pressure value of the pressure fluid delivered to the outlet 64 increases to a pressure value greater than 3,000 p.s.i., the force thereof acting against the end 123 of the valve member 114 together with the force of the intermediate fluid pressure acting on the end 124 of valve member 114 causes movement of the valve member 114 to the left in opposition to the force of the spring 128 thereby placing the ports 118 in fluid communication with the outlet 64. Since the annular groove 120 formed in the end of the member 114 permits throttling of the fluid from the outlet 64 into the ports 118, an intermediate pressure fluid is created by the control valve D which passes to the ports 118. As shown in FIGURES 5 and 6, the intermediate pressure is communicated to the chambers 94 of the motor C by the passage 90, the annular groove 89, and ports 105. The force of the intermediate pressure delivered to the chambers 94 respectively acts against the fins 84 and 85 in opposition to the torsional force of the spring 97 and cause counterclockwise rotation of the shaft 67 as viewed in FIGURE 2. Counterclockwise rotation of the shaft 67 by the force of the intermediate pressure conveyed to the chambers 94 by the control valve D causes counterclockwise rotation of the valve plate 38 as viewed in FIGURE 4, from its maximum displacement position toward its zero displacement position. Movement of the valve plate 38 past the position illustrated in FIGURE 9 providing zero displacement is prevented by the fins 84 and 85 abutting the respective stop means 92 and 91 (see FIGURE 8).

As previously described, when the valve plate is rotated from the position illustrated in FIGURE 4 toward the position illustrated in FIGURE 9, the displacement of the hydraulic apparatus A is decreased. Since the amount of fluid displaced by the hydraulic apparatus A from the inlet 63 to the outlet 64 is decreased, the pressure value of the pressure fluid in the outlet 64 is correspondingly decreased. When the pressure value of the pressure fluid in the outlet 64 drops to 3,000 p.s.i., the spring 128 acting in concert with the force of the intermediate fluid pressure acting on the end 124 of valve member 114 returns the valve member 114 to the position illustrated in FIGURE 2 thereby preventing further communication between the outlet 64 and the chambers 94 of the motor C. Since the fluid is now trapped within the chambers 94 by the control valve D and is non-compressible, the spring 97 cannot return the fins 84 and 85 against the respective stop means 91 and 92 (see FIGURE 7). Therefore, the valve plate 38 remains in its particular operating position providing for partial displacement of the hydraulic apparatus A.

If the pressure value of the pressure fluid delivered to the outlet 64, when the valve plate 38 is in a partial displacement position, should fall below 3,000 p.s.i., the spring 128 and the intermediate pressure acting on the end of valve member 114 will cause movement of the valve member 114 to the right from the position illustrated in FIGURE 2 thereby permitting fluid communication between the ports 118 and 119 through the annular groove 121. When the ports 118 and 119 are fluidly interconnected, the fluid within the chambers 94 is permitted to pass out through the passage 117 of the control valve D into the bore 70 of the motor C, and thus from the bore 70 to the inlet 63 by means of the passage 130. Since the chambers 94 are now vented to the inlet 63, the force of the torsional spring 97 causes rotation of the shaft 67 in a clockwise direction as viewed in FIGURE 2 effecting an increase in the displacement of the apparatus A until the pressure value in the outlet 64 reaches 3,000 p.s.i. whereby the control valve prevents further com-

munication between the chambers 94 and the inlet 63 or the fins 84 and 85 engage the stop means 91 and 92. If the fins 84 and 85 are returned against the stop 91 and 92, the valve plate 38 will be in the position illustrated in FIGURE 4 and thus provide for maximum displacement of the hydraulic apparatus A.

Therefore, it can be seen that the control valve D will tend to maintain the pressure value of the pressure fluid delivered to the outlet 62 by the hydraulic apparatus A at a predetermined selected pressure value, the control valve D and motor C cooperating to effect rotation of the valve plate 38 between the maximum and minimum displacement positions in order to cause the hydraulic apparatus A to deliver pressure fluid at the predetermined selected pressure value.

It can be seen that there has been described an improved hydraulic apparatus having means for varying the displacement thereof without changing the actual movement of the pistons or subjecting the apparatus to adverse cavitation conditions.

While this invention has been disclosed in connection with a certain specific embodiment thereof, it is to be understood that this is by way of example rather than limitation, and it is intended that the invention be defined by the appended claims.

What is claimed is:

1. A hydraulic apparatus comprising: a housing having a chamber and an inlet and an outlet leading respectively to and from said chamber; a block disposed in said chamber and having a cylinder formed therein; a piston disposed in said cylinder, said piston being adapted to be reciprocated relative to said block in order to provide an intake stroke and a discharge stroke; a movable valve plate disposed in said chamber between said block and said inlet and outlet and being adapted to interconnect said cylinder with said inlet and outlet; and means for moving said valve plate relative to said block to interconnect said cylinder with said inlet during at least a portion of said discharge stroke and with said outlet during at least a portion of said intake stroke to vary the displacement of said apparatus, said last-named means including a motor interconnected with said valve plate and comprising means defining a bore in said housing, a rotatable shaft disposed in said bore and being interconnected with said valve plate, biasing means operatively interconnected with said shaft and tending to maintain said valve plate in a predetermined rotational position relative to said housing providing for maximum displacement of said apparatus, means defining a motive surface on said shaft, and valve means for selectively applying and disapplying pressure fluid against said motive surface whereby the force of said

fluid acting against said motive surface rotates said valve plate from said predetermined position in opposition to said biasing means to decrease the displacement of said apparatus.

- 5 2. A hydraulic apparatus comprising: a housing having a chamber and an inlet and an outlet leading respectively to and from said chamber; a block disposed in said chamber and having a plurality of cylinders formed therein; a plurality of pistons disposed respectively in said cylinders, 10 said pistons each being adapted to be reciprocated relative to said block in order to provide an intake stroke and a discharge stroke; a movable valve plate disposed in said chamber between said block and said inlet and outlet and being adapted to interconnect said cylinders with said inlet and outlet; and means for moving said valve plate relative to said block to interconnect each cylinder with said inlet during at least a portion of the discharge stroke thereof and with said outlet during at least a portion of the intake stroke thereof to vary the displacement of said apparatus, 15 said last-named means including a motor interconnected with said valve plate and comprising means defining a bore in said housing, a rotatable shaft disposed in said bore and being interconnected with said valve plate, biasing means operatively interconnected with said shaft and tending to maintain said valve plate in a predetermined rotational position relative to said housing providing for maximum displacement of said apparatus, means defining a motive surface on said shaft, and valve means for selectively applying and disapplying pressure fluid against said motive surface whereby the force of said fluid acting against said motive surface rotates said valve plate from said predetermined position in opposition to said biasing means to decrease the displacement of said apparatus.
